(57) **CLAIM**

The ornamental design of a protective cover for a mobile computing device, as shown and described.

DESCRIPTION

FIG. 1 is front view of a design for a protective cover for use on the front of a mobile computing device, showing the protective cover on the front of an embodiment of a mobile computing device;

FIG. 2 is a frontal perspective view of the protective cover shown in FIG. 1 on the front of the mobile computing device shown in FIG. 1;

FIG. 3 is a rear view of the protective cover shown in FIGS. 1 and 2;

FIG. 4 is a side view of the protective cover shown in FIGS. 1-3, on the embodiment of mobile computing device shown in FIGS. 1 and 2; and,

FIG. 5 is a bottom view of the protective cover shown in FIGS. 1-4, in place upon the front of the embodiment of mobile computing device depicted by FIGS. 1, 2 and 4.

The dot-dash-dot broken lines in the drawings depict environment and form no part of the claim design.
